UNITED STATES PATENT OFFICE.

MIECZYSŁAW VON POKRZYWNICKI, OF WARSAW, RUSSIA.

STEAM BOILER.

Application filed February 9, 1914, Serial No. 817,506. Renewed January 20, 1922. Serial No. 530,639.

To all whom it may concern:

Be it known that I, MIECZYSŁAW VON POKRZYWNICKI, a subject of the Czar of Russia, and residing at Warsaw, in the Empire of Russia, have invented certain new and useful Improvements in Steam Boilers, of which the following is a specification.

This invention relates to steam generators, for use on locomotives and ships, the novelty 10 of which resides in the fact that the fire tubes located underneath the level of the water in the generator and connecting the fire chamber with the smoke chamber, are provided with superheaters, extending towards the firing chamber traversed by smoke tubes arranged in such a manner that between the former and the fire tubes annular spaces are formed through which the smoke gases can pass towards the smoke 15 chamber so that they heat, on the one hand, the water contained in the generator, and on the other, the superheater, provision being made by the smoke tubes traversing the superheater, for a considerable radiation 20 of heat to the superheater. By means of this arrangement the economy of steam superheating is increased to a very great extent and the steam in all parts of the superheater is uniformly heated. This construction dispenses with the various double 25 insulations which in other constructions are generally arranged along the superheater. In the case where the superheater becomes damaged the operation of the generator can 30 continue as it is only necessary to close the doors which shut off the fire tubes and which are located in the smoke chamber. By means of the proposed construction of the 35 generator, the advantage is obtained that less packing surfaces are needed and that rusting 40 cannot occur so that a cleansing is only necessary after a few thousand kilometres have been covered.

The accompanying drawings illustrate 45 two embodiments of the invention.

On the drawings:

Figure 1 is a longitudinal section through a locomotive generator provided with two superheaters. 50 Figure 2 is an end view of the superheater seen from the smoke chamber, partly in section on the line 1—1 of Figure 1.

Figure 3 is a longitudinal section through the front portion of the superheater showing a cooling device. 55

Figure 4 is a transverse section on the line 2—2 of Figure 3.

Figure 5 is a longitudinal section through a superheater having a different constructional form. 60

Fig. 6 is a transverse section on the line 6—6 of Figure 5.

In the locomotive boiler J of the usual construction, two fire tubes K are arranged which connect the fire box L with the smoke 65 chamber M. Each fire tube can be shut off from the smoke chamber by means of a door N. In each fire tube K a superheater C is mounted, the superheater bearing upon the frames A in such a manner that between 70 the fire tube K and the wall O of the superheater an annular chamber is formed through which the smoke gases originating in the fire box can pass to the smoke chamber M in order to heat, on the one hand, the 75 water contained in the boiler, and on the other hand, the surface of the superheater C. The superheater comprises also smoke tubes H whereby by means of the smoke traversing therethrough an intense heating 80 of the interior of the superheater can be produced. By incorporating baffle plates P the steam can be forced to traverse a path as long as possible provision being made for a uniform heating of all parts of the 85 steam. In order to make the superheating of the steam still more advantageous the superheater may be provided as shewn at Figure 5 with tubes Q arranged concentric with the tubes H, which are arranged in 90 such a manner that the steam first passes through the annular chamber and then returns through the superheating chambers, the steam being very rapidly superheated in the most advantageous manner as only thin 95 layers of it come into contact with the highly heated surface of the smoke tubes H.

The provision of a fire tube K in boilers is generally accompanied with great difficulties as the joints frequently become loose and then are not fluid-tight. 100 In order to avoid these drawbacks, the fire tube K according to this invention is undulated at

the end, as shewn at B, so that the pressure exerted by the expansion of the fire tube, on the wall of the firing chamber and of the smoke chamber, is eliminated.

- 5 As will be easily perceived, the end wall of the superheater is exposed to a very high temperature as it is in very close proximity to the firing chamber. In view of this and in order to obtain a fluid-tight joint between 10 the smoke tubes H which traverse the superheater, and the end wall R, the said tubes are welded to this wall by the aid of hydrogen, acetylene or similar gas. This may be done preferably by boring first of all the 15 holes in the end wall through which the tubes are to be passed, and after the superheater has been placed vertically, the openings may be sealed with iron, heating simultaneously the end wall and the smoke tubes, 20 with the aid of hydrogen or acetylene gas. In this connection care should be taken that the temperature of the end wall R and of the smoke tubes H, should be as constant and uniform as possible, in this manner a 25 very hermetic joint between these two parts is formed. When some time after one of the smoke tubes of the superheater burns through or bursts, it can be replaced by a new one in a very simple manner by simply 30 drilling out the tube, knocking it out and placing a new one in its stead. This can be effected in a very short time. When inserting a small number of tubes it is not necessary to place the superheater vertically. 35 Owing to the very high temperature of the gases striking the front end wall of the superheater, this wall is protected, according to the invention, from the detrimental effects of this temperature by a cooling insulating device illustrated in Figures 3 and 40. This device consists, preferably, of a suitable box S divided into chambers, which is mounted on the front end wall by means of a screw E. The hollow chambers of this 45 box are supplied with air, steam, exhaust steam or superheated steam directly from the superheater. The latter construction is shewn in the drawing. By means of a short tube C' the chambers of the insulating box 50 S, preferably made of sheets of cast steel or ordinary steel welded together, communicate with the interior of the superheater. From the chambers of the box S the steam is returned to the superheater through a

longer tube D. The latter is made longer because the steam flowing into the superheater alters its direction at the end wall R, so that if this tube D were short the flow of the steam in the superheater would afford a resistance to the return of the steam contained in the 60 box S. On the other hand, if the tube D is made too long, the flow of the steam in the superheater will produce a suction whereby the steam in the box S would be withdrawn. By means of a suitable arrangement of the 65 chambers of the box S (Figure 4) a uniform heating of the whole surface is obtained and as the superheated steam has a maximum temperature of 350° C., the end wall R of the superheater O and thus the ends of the 70 smoke tubes H are protected from the effect of the extremely high temperature of the smoke gases. The smoke tubes H communicate with the fire tube through suitable 75 apertures G formed in the box S. In order to facilitate the insertion of the tubes C and D, stays F may be screwed into the box S.

Having now particularly described and ascertained the nature of my said invention and in what manner the same is to be performed, I declare that what I claim is:—

1. In a boiler, the combination with a fire pipe, of a superheater disposed therein and comprising a casing terminating within the fire pipe, smoke pipes extending longitudinally throughout the casing and fixed to the ends thereof, and an independent casing fixed to the front end of the first mentioned casing and constructed to offer greater resistance to disintegration under the 90 action of heat than do the walls of the first mentioned casing, the two casings having means of intercommunication and the second mentioned casing having openings leading from the fire tube to the front ends of the 95 smoke tubes.

2. In a boiler, the combination with a fire pipe, of a superheater arranged therein and comprising a casing, a protective casing in advance of the first mentioned casing and connected thereto, a relatively short pipe affording communication between the upper 100 portions of the casings, and a relatively long pipe affording communication between the lower portions of the casings.

In testimony whereof I affix my signature.

MIECZYSLAW von POKRZYWNICKI.
